UNITED STATES PATENT OFFICE.

WILFRID HENRY CALNAN, OF LONDON, ENGLAND.

RECEPTACLE FOR CONTAINING POWDER PUFFS AND POWDER FOR TOILET PURPOSES.

Application filed June 19, 1925, Serial No. 38,232, and in Great Britain June 4, 1924.

This invention relates to receptacles for containing powder puffs and powder for toilet purposes and it has for its object certain improvements designed to facilitate 5 the replenishing of the supply of powder without wasting or spilling same.

According to this invention a sieve is employed mounted without the aid of gummed strips, adhesive or other means calculated to 10 secure a more or less permanent fixing of the same in such manner as to permit of its being readily removed or displaced to expose the full or substantially the full opening in the receptacle for the introduction 15 of the powder.

In order that the invention may be better understood drawings are appended illustrating two forms of the invention as applied to a known type of device embodying 20 a rigid receptacle and as applied to a device embodying a receptacle in the form of a flexible body provided with a spring whereby said body is normally distended and having a sieve mounted therein and a 25 lid or cover, in which:

Fig. 1 is an elevation showing the receptacle closed,

Fig. 2 is a vertical section,

Fig. 3 is a plan showing the receptacle 30 closed,

Fig. 4 is a plan showing the receptacle open,

Fig. 5 is a sectional view showing the invention applied to a receptacle in which the 35 powder containing portion is formed of rigid material.

The powder is carried in a round shallow receptacle *a* having an upstanding flexible side wall *a*² receiving a supporting ring *b* 40 in the upper part of the receptacle to which the upper edge of said wall is secured. An intermediate dish-shaped ring *b*¹ having an upper lateral flange resting on said supporting ring, has an inner lower flange *b*², and 45 an intermediate main portion *b*³ received in said supporting ring with a friction fit and projecting a distance below said supporting ring *b*.

A perforate member or sieve *c* is secured 50 on said lower flange for the reception of a powder puff *c*' thereon substantially below the upper face of the intermediate ring *b*.

A helical spring *e* engaging between said ring *b* and the bottom of the receptacle and 55 having its upper convolution disposed between said intermediate portion *b*³ and said

wall *a*' keeps the receptacle distended whereby any clogging or caking of the powder is prevented.

A pair of widely spaced ears *k* mounted 60 fast on said supporting ring carry a pin *l* passed through said ears and pivotally receiving an ear *n* mounted fast on said intermediate ring *b*' and pivoted on the pin midway between said spaced ears *k*, whereby 65 the intermediate ring is hinged on the supporting ring.

A cover *h* resting on said intermediate ring *b*' is provided with ears *m* pivoted on said pin between the ears of the supporting ring and the ear of the intermediate ring whereby the cover is hinged on the ring *b* over the ring *b*'. A catch *i* on the receptacle holds the cover closed.

Any other provision may, however, be 75 made for securing the parts closed, such provision, however, being preferably such that while the opening of the lid or cover may be readily effected the fastening for the sieve carrying member is not so apparent 80 or so readily operable.

The interior of the lid may also, in this case, be highly polished to serve as a mirror, or a mirror may be secured thereto.

When it is desired to apply powder to puff 85 *e*', the bottom of the receptacle is pressed with the hand or against some suitable support, collapsing the receptacle and pressing the powder through the sieve to the puff. The collapsibility of the receptacle permits 90 it to be reduced to its smallest dimensions for carrying.

Instead of employing a body formed of flexible material a rigid material may be employed for this purpose the sieve and lid 95 being hingedly mounted therein with a hinged lid.

Such an arrangement is shown in Fig. 5, on reference to which it will be seen that the spring *e* is omitted and the lid *h* and 100 sieve carrying body *g*' are hingedly connected to the body *a*'' in the same manner as in Figs. 1 to 4.

I claim as my invention:

1. In combination, a receptacle; a supporting ring in the upper part of the receptacle; an intermediate dish shaped ring hinged and resting on said supporting ring; a sieve secured in said intermediate ring; a pair of widely spaced ears mounted fast on said supporting ring; a pin passed through said ears; an ear mounted fast on said intermedi-

- ate ring and pivoted on said pin midway between said spaced ears, whereby the intermediate ring is hinged on the supporting ring; and a cover resting on said intermediate ring and provided with ears pivoted on said pin between the ears of the supporting ring and the ear of the intermediate ring.
- 5 2. In combination, a receptacle having a flexible side wall; a supporting ring in the upper part of the receptacle; an intermediate dish shaped ring hinged and resting on said supporting ring; a sieve secured in said intermediate ring; a helical spring compressed between said supporting ring and the bottom of the receptacle and partly surrounding the dish shaped ring; a perforate member secured in said intermediate ring; and a cover resting on said intermediate ring and hinged to the supporting ring.
- 10 3. In combination, a round shallow receptacle having an upstanding flexible side wall; a supporting ring in the upper part of the receptacle to which the upper edge of the wall is secured; an intermediate disk shaped ring hinged to said supporting ring and having an upper lateral flange resting on said supporting ring, an inner lower flange and an intermediate main portion received in said supporting ring projecting a
- 15 distance below said supporting ring; a helical spring engaging between said ring and the bottom of the receptacle and having its upper convolution disposed between said in-
- termediate portion and said wall; a sieve secured on said lower flange for the reception of a powder puff thereon; and a cover on said intermediate ring.
- 20 4. In combination, a receptacle; an intermediate dish shaped ring having an upper lateral flange resting on the upper edge of said receptacle, an inner lower flange and an intermediate main portion projecting a distance below said upper flange; a sieve secured on said lower flange for the reception of a powder puff thereon substantially below the upper face of the ring; and a cover resting on said ring and hinged to the receptacle.
- 25 5. In combination, a round shallow receptacle having an upstanding side wall; a supporting ring secured in the upper part of the receptacle; an intermediate dish shaped ring having an upper lateral flange resting on said supporting ring, an inner lower flange and an intermediate main portion received in said supporting ring with a friction fit and projecting a distance below said supporting ring; a sieve secured on said lower flange for the reception of a powder puff thereon substantially below the upper face of the intermediate ring; and a cover resting on said intermediate ring and hinged to the supporting ring.

In testimony whereof I have hereunto set my hand.

WILFRID HENRY CALNAN
